UNITED STATES PATENT OFFICE.

ARTHUR P. WOLFE, OF BUFFALO, NEW YORK, ASSIGNOR TO NIAGARA MACHINE AND TOOL WORKS, OF BUFFALO, NEW YORK.

SCREW-THREADING AND BEADING MACHINE.

SPECIFICATION forming part of Letters Patent No. 716,162, dated December 16, 1902.

Application filed April 14, 1902. Serial No. 102,856. (No model.)

To all whom it may concern:

Be it known that I, ARTHUR P. WOLFE, a citizen of the United States, residing at Buffalo, in the county of Erie and State of New York, have invented new and useful Improvements in Screw-Threading and Beading Machines, of which the following is a specification.

This invention relates to a machine for screw-threading or beading sheet-metal jar or bottle caps and similar articles.

The object of the invention is to provide a machine of large capacity which is simple in construction and which is readily adapted for forming screw-threads or beads on sheet-metal caps or the like of different sizes and forms.

The machine hereinafter described, and shown in the drawings as an embodiment of the invention, briefly stated, is organized and operates as follows: The blank caps are received from a feed-chute and carried by a reciprocating feed device to and placed on the rotary forming-chuck. Before the feed device is retracted a rotary die-roll is advanced toward the chuck, and a flange on the die-roll engages between the cap and the feed device and holds the blank on the chuck when the feed device returns. The chuck and die-roll are provided, respectively, with a projecting thread and a peripheral co-operating groove which as the cap is rolled between the oppositely-rotating chuck and die-roll form the screw-thread. After the thread is formed the die-roll is moved away from the chuck, and a knock-out rod, which is arranged axially in the hollow chuck-spindle, is projected to engage the cap and push the same off of the chuck.

In the accompanying drawings, consisting of two sheets, Figure 1 is a plan view of a machine embodying the invention, the feed-chute being removed. Fig. 2 is a perspective of the machine looking from the left in Fig. 1. Fig. 3 is a transverse vertical section on the line 3-3, Fig. 1, through the carriage for the die-roll. Fig. 4 is a vertical section on the line 4-4, Fig. 1, through the die-roll carriage. Fig. 5 is a transverse section through the feed-chute. Fig. 6 is a broken elevation of the feed-chute and feed device, on an en-

larged scale. Fig. 7 is a sectional view through the feed-chute and feed device on the line 7-7, Fig. 6. Fig. 8 is a fragmentary sectional view through the feed-chute and feed device, showing the latter in position to receive a blank from the hopper. Fig. 9 is a section through the feed device on the line 9-9, Fig. 6, and showing the die-roll in position to remove the blank from the feed device. Fig. 10 is a fragmentary elevation, on an enlarged scale, of the forming-chuck, showing another form of knock-out rod. Fig. 11 is a vertical section through the parts shown in Fig. 10.

Like letters of reference refer to like parts in the several figures. 65

A represents a base or bed plate of any desired form which supports the several operating parts of the machine. In the construction shown in the drawings the base-plate is provided intermediate of its ends at the front side or portion with an opening a, through which the threaded caps can fall when removed from the chuck.

B represents the rotary forming chuck or mandrel, which is arranged over the opening a and is carried by the end of a hollow spindle C, which is journaled in suitable bearings c on the head-stock c', which is adjustable toward and from the opening a in a way c² in the base-plate. The head-stock is adjusted by means of a hand-wheel or the like c³. 70 80

c⁴ represents clamping-bolts for holding the head-stock in adjusted position at one side of the opening a. The chuck shown in the drawings is intended for forming screw-threads on sheet-metal jar and bottle caps or the like and for this purpose is provided with a helical raised thread or bead. The chuck is detachably secured to the spindle in any suitable manner. It is shown as being provided with an internal screw-thread which is screwed onto a reduced screw-threaded portion of the spindle. 85 90

D represents a cone-pulley or the like secured to the chuck-spindle between the bearings c for driving the spindle. 95

E represents the threading die-roll, which is provided with a helical groove and is so arranged and proportioned relative to the chuck 100

that when the two are driven in opposite directions the bead on the chuck is adapted to follow the groove in the die-roll and form the thread on the cap, which is rolled between the mandrel and die-roll in a well-known manner. The die-roll is provided at its end opposite the end of the chuck with an annular beveled flange e , the purpose of which will be hereinafter explained. The die-roll is secured to a shaft F , journaled in suitable bearings carried by a carriage G , which is mounted to reciprocate back and forth on the base-plate. The carriage and guides therefor may be of any suitable construction. In the construction shown in the drawings the carriage (see Fig. 4) is provided with side flanges g , which slide in grooves formed in raised portions g' of the base-plate. The carriage is held in its grooves by strips or bars g^2 , which are secured to the base and overhang the flanges of the carriage. The bearings h for the die-roll shaft F are formed on a block H , which is adjustably mounted on the reciprocating carriage, so that the die-roll can be properly adjusted relative to the chuck. The reciprocating carriage G is provided in its upper face with a groove or channel in which engages a longitudinal tongue h' on the under side of the bearing-block H .

h^2 represents an adjusting - screw which passes through a screw-threaded opening in a lug on the reciprocating carriage and abuts against the rear end of the bearing-block. The block is fixed in adjusted positions by a clamp - bolt h^3 on the carriage and which passes through an elongated slot h^4 in the bearing-block.

The die-roll is driven from the chuck-spindle by suitable gearing, which may be of any preferred construction or arrangement. In the drawings a jointed or flexible shaft I is shown which is arranged in rear of the chuck-spindle and is journaled at its outer end in a bearing i on the head-stock and at its inner or opposite end in a bearing i' , formed on the bearing-block for the die-roll. The outer end of the chuck-spindle is provided with a gear-wheel i^2 , geared to a gear-wheel i^3 on the outer end of the jointed shaft I by a change-gear wheel i^4 , whereby the jointed shaft can be driven at different speeds from the chuck-spindle. The inner end of the jointed shaft is provided with a gear-pinion j , which meshes with and drives a gear-pinion j' , fixed to the adjacent end of the die-roll shaft. As the carriage for the die-roll is reciprocated back and forth a loose connection of the jointed shaft I in one of its bearings is necessary, and for this purpose the inner end of the jointed shaft is shown as slidably engaging in its bearing and is provided with a key-groove j^2 , in which slides a key on the gear-pinion j , which is confined in a groove or pocket in the bearing for the flexible shaft, so as to be held from longitudinal movement.

The mechanism shown for reciprocating the

die-roll carriage is constructed as follows: K represents a cam-shaft which is journaled in suitable bearings k on the rear portion of the base-plate. This shaft is preferably driven by means of a belt-pulley k' , which is secured to the shaft between its bearings. The reciprocating carriage is provided with a rear-wardly-extending arm k^2 , the rear end of which is bifurcated and straddles the shaft K , adjacent to the drive-pulley k' . The arm k^2 is provided with a stud which extends from the same into a cam-groove k^3 , formed in the adjacent face of the drive-pulley, and is preferably provided with an antifriction - roller. The cam-groove is provided with a concentric portion of small radius extending substantially throughout half a circle and with a concentric portion of greater radius extending through somewhat less than half a circle and which joins the other concentric portion by means of inclined or cam portions. The shape of the cam-groove is such as to advance the carriage and hold the same, with the die-roll, in operative engagement with the cap on the chuck until the thread is formed and then retract the carriage and retain the same in the retracted position for a period of time sufficient to permit the finished cap to be removed from the chuck and a blank cap placed thereon.

The mechanism shown in the drawings for feeding the blank caps to the chuck is constructed as follows: L , Figs. 2, 6, 7, and 9, represents a feed chute or box which is supported in an inclined position over the opening a in the front of the base-plate, with its lower open end somewhat above the plane of the forming-chuck. The feed-chute is preferably provided with adjustable guide-plates l , which extend longitudinally through the chute and are adapted, by adjusting the same toward or from each other, to regulate the size of the chute to suit different-sized caps. The guide-plates are carried at the inner ends of adjusting - screws l' , which are screwed through openings in the sides of the chute and are provided with jam-nuts or the like l^2 for holding them in adjusted position. M represents a feed bar or rod which is arranged substantially in line with the chuck-spindle and slidably mounted in bearings m on the base-plate, so as to move toward and from the chuck. The feed-bar is provided at its inner end or end adjacent to the chuck with a head m' , which is preferably detachably secured thereto in any preferred manner—for instance, by screws m^2 , Fig. 7. The head is provided at its forward end with a flange m^3 , the lower part of which is curved and forms a support for the blank cap and which in the retracted or outer position of the feed-bar stands beneath the lower end of the feed-chute, so that a cap-blank can fall from the chute onto the flange m^3 , as shown in Fig. 8. The head is provided at the rear upper side opposite the flange m^3 with a projecting fin-

ger or portion m^4 , which prevents the escape of the cap from the rear side of the head. When the head is beneath the lower end of the chute, the lowermost cap will rest on the flange m^3 and will support the other caps in the chute above it.

5 N represents a retaining-strip which is secured at its outer end to the feed-bar and at its inner end is deflected downwardly and rests upon the head on the feed-bar. In the reciprocation of the feed-bar this retaining-strip passes beneath the open end of the chute and supports the caps, as shown in Fig. 7. The strip is preferably adjustably secured to the feed-bar by means of a bolt n' , which passes through an elongated slot in the retaining-strip and is provided with clamping-nuts n' on opposite sides of the retaining-strip. The blank caps are supplied 20 to the feed-chute so that they will drop on the feed-head with their open ends toward the chuck.

To prevent the blank caps from jumping or bouncing out of the feed-head when they 25 drop into the same from the feed-chute, a swinging gate S is provided. As shown, this gate is hinged to the lower end of one of the guide-plates l in the chute and is adapted to hang down vertically and rest against the 30 end of the feed-head. The weight of the swinging gate is sufficient to prevent the caps from forcing the same upwardly and escaping from the head. When the head is moved toward the chuck, it engages the gate 35 and swings it up into the position shown in Fig. 7, in which position the gate is supported by portions s at the sides of its lower end which rest on the upper faces of the flange m^3 and finger m^4 of the feed-head. 40 When the head is returned, the swinging gate falls again into the position shown in Fig. 8 before a blank cap passes into the head.

When the feed-bar is moved toward the chuck, the cap, which is larger than the chuck, 45 is engaged over the latter. Before the feed-rod is returned the die-roll is advanced and the flange e thereof engages between the head of the cap and the back of the feed-head, as shown in Fig. 9, and holds the cap 50 on the chuck until the thread is formed.

O represents an operating-lever for the feed-bar. The lever is fulcrumed on a vertical pin p , rising from the base-plate, and at its rear end is provided with a stud p' , which 55 engages in a peripheral groove in a cam P , secured to the cam-shaft K . The stud may be provided with an antifriction-roller, if desired. The forward arm of the lever O is provided with a yielding extension O' , the forward 60 end of which engages loosely in a slot in the feed-bar M . The lever extension is preferably pivoted in a bifurcation at the forward end of the lever O and is provided with an offset rear end which extends up beside 65 the forward arm of the lever and is provided with a shoulder q , adapted to strike against

the lever, whereby the extension is caused to move with the lever when the latter is moved in one direction. The rear end of the extension is connected to one end of a spiral spring q' , the other end of which is connected to the lever. The spring is preferably connected to the lever by an adjusting-bolt q^2 , which is screwed into a lug on the lever O and is provided with a holding jam-nut q^3 . By adjusting this connection the tension of the spring can be regulated. When the lever is rocked by its cam to move the feed-bar toward the chuck, the spring connecting the lever and lever extension causes the latter to move with the cam-lever and move the feed-bar. When the lever is rocked in the opposite direction, the engagement of the lever with the shoulder on the lever extension will cause the latter to move with the lever and retract the feed-bar. If a blank cap is improperly placed in the feed-chute with its head toward the chuck, when the feed-bar is advanced the head of the cap will strike the chuck and prevent further movement of the feed-bar. The yielding connection between the lever and its extension permits the feed-bar to be arrested without crushing the cap or injuring the machine. The die-roll is advanced while the cap is still held between the chuck and feed-head, 95 so that its flange e will extend through the opening between the lower end of the flange m^3 and the portion m^4 on the feed-head and strike the cap, forcing it out of the head, so that the latter will properly feed the next cap. 100

R represents a knock-out rod for moving the threaded caps from the chuck. This rod extends axially through the hollow chuck-spindle and is operated by the following means: r represents a lever which is pivoted intermediate of its ends on a pin rising from the forward portion of the head-stock with its outer end engaging loosely in a slot in the outer end of the knock-out rod. The opposite arm of the lever is connected by a link r' to one arm of a tappet-lever r^2 , which is fulcrumed on the base-plate adjacent to the drive-pulley k' on the cam-shaft. The other arm of the lever r^2 extends toward said pulley in the path of a tappet lug or projection r^3 115 on the pulley. When the projection strikes the tappet-lever r^2 , the latter is moved to push on the connecting-link r' and swing the lever r , so as to move the knock-out rod inwardly and push the cap off of the chuck. The 120 knock-out rod is returned to its normal position by a spring r^4 , which is shown as connected at one end to the tappet-lever r^2 and at its other end to a suitable fixed part, such as a pin r^5 , on the adjacent bearing k of the 125 cam-shaft K .

In Figs. 10 and 11 is shown a slightly-different construction of knock-out rod, which is adapted for removing annular screw-rings or the like from the chuck. A screw ring or cap 130 having a central opening cannot be removed by the knock-out rod shown in Fig. 1, as the

same would pass through the opening in the head of the cap or ring. In the construction shown in Figs. 10 and 11 the inner end of the knock-out rod T is provided with radial 5 arms or pins t, which extend through elongated slots t' in the chuck-spindle and connect the knock-out rod with a ring l', surrounding the chuck-spindle. When the knock-out rod is moved inwardly, the ring is carried 10 with it and slides over the chuck, pushing the ring or cap from the latter.

The operation of the machine is as follows: The blank caps are supplied to the feed-chute L with their open ends toward the chuck B 15 by the cap-forming machine or in any suitable manner and are placed successively on the chuck by the reciprocating feed device M, as before explained. After a cap has been placed on the chuck the die-roll E is advanced 20 by the operating-cam k', as above described, until the die-roll engages the cap on the chuck, and the feed device M is returned to its normal position to receive another cap. The 25 annular flange e on the die-roll enters between the head of the cap and the back of the feed-head and prevents the head from carrying the cap with it when it returns or moves away from the chuck. The die-roll and chuck rotating in the opposite direction roll the cap 30 on the chuck and form the thread. When the thread is completed, the die-roll is retracted by its cam, and while retracted the tappet lug or projection r' on the drive-pulley k' engages the tappet-lever r'' and through 35 the connections above described moves the knock-out rod R inwardly, so as to strike the cap and shove the same from the chuck.

In certain classes of work it is desirable to rotate the forming-chuck and die-roll slower 40 than in other classes of work. With the separate drives for the chuck-shaft and the cam-shaft for operating the feed and knock-out devices it is possible to retard the speed of the chuck and die-roll without retarding the 45 speed of the feeding mechanism, and thus reducing the output of the machine. The sliding carriage for the die-roll provides a simple and strong construction in which the necessary pressure for forming the thread or bead 50 is obtained. To operate upon blanks of different size, it is only necessary to detach the feed-head and replace the same by one of suitable size, place a chuck and die-roll of proper size on the spindle and die-roll shaft, and put 55 in the proper change-gear between the chuck-shaft and the jointed drive-shaft for the die-roll.

While a machine for forming screw-threads on caps and the like has been particularly 60 described, the machine is equally adapted for producing annular beads or other classes of work by simply substituting properly-formed chucks and dies for the threading chuck and die.

65 I claim as my invention—

1. The combination of a rotary chuck, a ro-

tary die, means for moving said die toward and from said chuck, a flexible rotary shaft geared to said die to rotate the latter, a feed device which receives the caps, and means 70 for moving said feed device toward and from said chuck, substantially as set forth.

2. The combination of a chuck, a rotary spindle carrying said chuck, a rotary die, means for moving said die toward and from 75 said chuck, a flexible shaft geared to said chuck-spindle and to said die, a feed device which receives the caps, and means for moving said feed device toward and from said chuck, substantially as set forth. 80

3. The combination of a rotary chuck, a rotary die, means for moving said die toward and from said chuck, a feed device provided with a head in which a cap is adapted to rest, means for moving said feed device toward and 85 from said chuck, said die having a part adapted to extend into said feed-head to engage the cap and disengage the same from said feed-head when the latter moves away from said chuck, substantially as set forth. 90

4. The combination of a rotary chuck, a rotary die, means for moving said die toward and from said chuck, a feed device which receives the caps, and a yielding device for moving said feed device, said die having a part 95 adapted to engage the cap and disengage the same from said feed device when the latter moves away from said chuck, substantially as set forth.

5. The combination of a rotary chuck, a rotary die, means for moving said die toward and from said chuck, a feed device which receives the caps, an operating-lever for said feed device having a yielding arm, and means for operating said lever, said die having a 105 part which is adapted to engage the cap and disengage the same from said feed device when the latter moves away from said chuck, substantially as set forth. 100

6. The combination of a rotary chuck, a rotary die, means for moving said die toward and from said chuck, a feed-chute, a feed device movable beneath said chute toward and from said chuck and adapted to receive the caps from said chuck, and a yielding device 115 carried by said chute and extending into proximity to said feed device to prevent the caps from falling off of said feed device, substantially as set forth. 110

7. The combination of a rotary chuck, a rotary die, means for moving said die toward and from said chuck, a feed-chute, a feed device movable beneath said chute toward and from said chuck and adapted to receive the caps from said chute, and a plate hinged to 125 said chute and which extends downwardly in front of said feed device to prevent the caps from falling from the latter, substantially as set forth. 120

8. The combination of a rotary chuck, a rotary die, provided with an annular flange, means for moving said die toward and from 130

said chuck, a feed-head movable toward and from said chuck and adapted to receive a cap, said die-flange being adapted to enter said feed-head to engage the end of the cap and hold the latter on said chuck when said feed-head moves away from said chuck, substantially as set forth.

Witness my hand this 27th day of March, 1902.
